UNITED STATES PATENT OFFICE.

MATTHEW DAVING, OF PITTSBURGH, PENNSYLVANIA.

DESIGN FOR A LAMP-STANDARD.

44,749.

Specification for Design.

Patented Oct. 21, 1913.

Application filed August 19, 1913. Serial No. 785,567. Term of patent 7 years.

To all whom it may concern:

Be it known that I, MATTHEW DAVING, a citizen of the United States, residing at Pittsburgh, in the county of Allegheny and State of Pennsylvania, have invented a new, original, and ornamental Design for a Lamp-Standard, of which the following is a specification, reference being had to the accompanying drawing, forming part thereof.

The figure is a perspective view of a lamp standard showing my new design.

I claim:—

The ornamental design for a lamp standard as shown.

MATTHEW DAVING.

Witnesses:

F. E. GAITHER,
W. G. DOOLITTLE.
